(57) CLAIM

The ornamental design for an artware as shown and described.

DESCRIPTION

FIG. 1 is a front side perspective view of an artware showing my new design;

FIG. 2 is a rear side perspective view thereof;

FIG. 3 is a left side perspective view thereof;

FIG. 4 is a right side perspective view thereof;

FIG. 5 is a top perspective view thereof;

FIG. 6 is a bottom perspective view thereof; and,

FIG. 7 is a top, front and left perspective view of the artware. The ghosted areas in the drawings depict portions of the artware that form no part of the claimed design.
